United States Patent Office

Des. 228,871

Patented Oct. 30, 1973

228,871

KNIFE SHARPENER OR SIMILAR ARTICLE

Ross F. Pollard, Amesbury, Mass., assignor to Towle
Manufacturing Company, Newburyport, Mass.

Filed July 10, 1972, Ser. No. 270,012

Term of patent 14 years

Int. Cl. D8—05

U.S. Cl. D8—93

FIG. 1

FIG. 2

FIG. 3

FIG. 4

FIG. 1 is a top plan view of a knife sharpener or similar article showing my new design;

FIG. 2 is a side view, the opposite side of which is identical;

FIG. 3 is an end view, as seen from the righthand side of FIG. 1; and

FIG. 4 is an end view as seen from the lefthand side of FIG. 1.

I claim:

The ornamental design for a knife sharpener or similar article, substantially as shown and described.
